D. B. ABBOTT

BOOT OR SIMILAR ARTICLE

Filed May 1, 1924

Donald B. Abbott ^{Inventor}
By his Attorney
Phillips Abbott

Patented May 12, 1925.

Des. 67,254

UNITED STATES PATENT OFFICE.

DONALD B. ABBOTT, OF YARMOUTH, MAINE.

DESIGN FOR A BOOT OR SIMILAR ARTICLE.

Application filed May 1, 1924. Serial No. 9,460. Term of patent 3½ years.

To all whom it may concern:

Be it known that I, DONALD B. ABBOTT, a citizen of the United States, residing at the town of Yarmouth, in the county of Cumberland and State of Maine, have invented a new, original, and ornamental Design for Boot or Similar Article, of which the following is a specification, reference being had to the accompanying drawing, forming part thereof.

The figure is a side view of the boot or similar article showing my new design.

I claim—

The ornamental design for a boot or similar article as shown.

DONALD B. ABBOTT.
